UNITED STATES PATENT OFFICE.

HUBERT MEREDITH-JONES, OF NEW YORK, N. Y.

PNEUMATIC CLEANER.

1,114,171.

Specification of Letters Patent. Patented Oct. 20, 1914.

Application filed November 15, 1912. Serial No. 731,547.

To all whom it may concern:

Be it known that I, HUBERT MEREDITH-JONES, a subject of the King of England, and a resident of New York, county and State of New York, have invented a certain new and useful Improvement in Pneumatic Cleaners, of which the following is a full, clear, and exact specification.

This invention relates more particularly to a class of pneumatic devices adapted to be used for cleaning articles made especially of fabricated materials.

My invention has for its object primarily to provide a form of device which is constructed so as to permit it to be manually operated for employing currents of air by which carpets, rugs, draperies, and like household furnishings may be effectually cleaned, thereby saving the irksome work incident to the use of a broom, brush, or other methods ordinarily used for cleaning especially in homes. This is accomplished mainly by providing a form of cleaner wherein is employed a rotatable fan for producing currents of air by which dust, or the like is suctionally extracted from the articles being cleaned.

Another object of the invention is to provide means adapted to permit the fan to be manually revolved at a desired speed; and still another object of the invention is to provide a receiver by which dust may be collected, and which permits the refuse to be readily removed from the device when desired.

A further object of the invention is to provide a pneumatic cleaner of simple and efficient construction, and which may be made light in weight as well as susceptible of being readily operated.

A practical embodiment of the invention is represented in the accompanying drawing forming a part of this specification in which similar characters of reference indicate corresponding parts in all the views, the said invention being more fully described hereinafter and then pointed out in the appended claims.

In the drawing, Figure 1 is a side elevation of one form of pneumatic cleaner embodying my invention. Fig. 2 is a longitudinal section, partly fragmentary and partly in detail, of the cleaner. Fig. 3 is a section taken on the line II-II of Fig. 2.

Fig. 4 is a section taken on the line III-III of Fig. 2. Fig. 5 is a view of the ring for supporting one end of the woven bag used in the device. Fig. 6 is a fragmentary side view of the woven bag. Fig. 7 is a side view of the supporting bracket used in the cleaner.

The device, or pneumatic cleaner has a barrel or tubular casing 10 which is preferably circular in shape, and said barrel may be of any suitable circumference and length. Around the exterior of the barrel 10, and in proximity to one end thereof, is spun a rib 11 whereby an inner annular groove 12 is provided. The end portion of the barrel 10 which is contiguous to the rib 11 may be slightly tapered and tightly fitting this tapered end is a cap 13 which carries a tube 14. The tube 14 is preferably of sufficient length to extend some distance interiorly of the barrel 10 as well as extending a suitable distance beyond the exterior of the cap, and upon the free end of this extension is attached one end of a pipe 15 having a nozzle, as 16, of the usual, or any preferred form, mounted upon its opposite end.

The end of the barrel 10, which is opposite to the cap 13, is soldered, or otherwise connected to a concentric rib, or flange 17 formed upon the edge of the large opening, as 18, through the underside of a head 19 which is hollow so as to provide a chamber 20, and projecting from the center of the exterior of said head which is opposite to the large opening 18 is a boss 21. Through the boss 21 is a threaded opening which is in register with an opening also formed through the head, and in said head are outlet ports, as 21a. In the opening of the boss 21 is threaded a screw 22 having a concaved, or tapered recessed end, and upon the outer end of said boss is a handle 23 for permitting the device to be carried in the hand of a person.

Lengthwise through the barrel 10 and adjacent to the head 19 is an elongated opening 22a, and upon the exterior of the barrel at the edge of this opening is a housing 23a. In the side walls of the housing is pivoted a transverse short shaft 24, and at one end of the shaft is held one end of a bracket 25. This arm of the bracket 25 extends through an elongated opening in the barrel to approximately the center thereof where it is

connected to one end of a cross-plate 26, and the other end of the bracket is fastened to the concentric rib 17 of the head 19. In a threaded opening through the cross-plate 26 is an adjustable screw 27 having in its end, which is opposed to the screw 22, a concaved or tapered recess. Rotatably seated in the tapered recess of the screw 27 is one of the pointed or tapered ends of a shaft 28. The opposite end of the shaft 28 is also pointed, or tapered, and is rotatably seated in the tapered recess of the screw 22.

Upon the shaft 28, and within the chamber 20 of the head 19, is a fan 29 having a plurality of radially disposed blades 29^a which are of a formation and arrangement so that when revolved suctional currents of air will be forced through the nozzle 16, through the pipe 15, through the tube 14, and into the barrel 10. From the barrel 10 the air will be forced into the chamber 20 of the head 19, and exhausted through the outlet ports 21^a in said head.

On a portion of the shaft 28 which is adjacent to the screw 27 is a worm 30, and meshing with said worm is a ratchet toothed wheel 31 which is mounted upon the short shaft 24 so as to be rotatable in the housing 23. Serving to permit the ratchet wheel 31 to be manually rotated to operate the worm 30 for revolving the shaft 28, whereby the fan 29 may be operated, on the short shaft 24 and exteriorly of the barrel 10 is a crank handle 32. When the cleaner is in use it is carried and guided over the article being cleaned by the handle 23 in one hand of the person operating it, and through the arrangement of the crank handle 32 the device may be conveniently operated at the same time by the other hand of the person.

For the purpose of collecting the dust, or refuse which is admitted into the barrel 10 through the nozzle 16, the pipe 15, and the tube 14, I provide a receiver, or bag, as 33, which is made of cloth, or other suitable woven material having interstices therethrough. One end of the intersticed receiver, or bag 33 is fastened to a split ring 34 which is preferably made of spring metal so as to be sprung into the annular groove 12 of the barrel 10. The opposite end of the bag 33 is connected to the free end of a bracket 35 which is formed of two substantially U-shaped members of wire, or other metal projecting inwardly of the barrel 10 from the tube 14, and which are disposed in cross-wise arrangement. When the admixture of air and dust is admitted into the barrel 10 it is received by the bag 33. The air will pass through the interstices of the bag while the dust will be collected upon the inner surface thereof, and when it is desired to empty the bag of accumulated refuse the cap 13 is removed from the tapered end of the barrel 10. The tube 14,

the bracket 35, and the bag 33 will thereby be directed outwardly of the barrel 10, and the bag may be emptied of its refuse in any suitable manner.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:—

1. In a pneumatic cleaner of the character described, having a barrel, a removable cap, a tube therethrough adapted to carry a nozzle and means for suctionally drawing the dust into the barrel, the combination of an intersticed receiver disposed within the barrel and having one of its ends detachably mounted to the barrel adjacent to the cap, a bracket connected to the tube of the cap and fastened to the opposite end of the receiver so that said receiver may be withdrawn from the barrel when the cap is removed therefrom.

2. In a pneumatic cleaner of the character described, having a barrel, a removable cap provided with a tube adapted to carry a nozzle, means for suctionally drawing dust into the barrel, and spring actuated means within the barrel adjacent to said cap, the combination of a cloth bag disposed within the barrel, and having its mouth secured to the spring actuated means, and means connecting the opposite end of the bag to the tube of the cap, whereby the bag may be withdrawn from the barrel when the cap is removed therefrom.

3. In a pneumatic cleaner of the character described, having a barrel, a removable cap provided with a tube adapted to carry a nozzle, means for suctionally drawing dust into the barrel, and spring actuated means within the barrel adjacent to said cap, the combination of a cloth bag disposed within the barrel, and having its mouth secured to the spring actuated means, and a substantially U-shaped member connecting the opposite end of the bag to the tube of the cap, whereby the bag may be withdrawn from the barrel when the cap is removed therefrom.

4. In a pneumatic cleaner of the character described, having a barrel, a removable cap provided with means for removably retaining a nozzle thereto, in combination with a flexible intersticed receiver mounted in the barrel so as to be adapted to be withdrawn therefrom, spring actuated means within the barrel, and removably holding one end of

the receiver therein, and a plurality of substantially U-shaped members connected to the cap and to the other end of the receiver, whereby the receiver may be withdrawn from the barrel when the cap is removed therefrom.

This specification signed and witnessed this fourteenth day of November A. D. 1912.

HUBERT MEREDITH-JONES.
